UNITED STATES PATENT OFFICE.

EDWARD B. WESTON, OF DAYTON, OHIO.

PRINTING DEVICE FOR WRAPPING-PAPER ROLLS.

SPECIFICATION forming part of Letters Patent No. 406,319, dated July 2, 1889.

Application filed July 9, 1888. Serial No. 279,399. (No model.)

To all whom it may concern:

Be it known that I, EDWARD B. WESTON, a citizen of the United States, residing at Dayton, in the county of Montgomery and State of Ohio, have invented a certain new and useful Improvement in Printing Devices for Wrapping-Paper Rolls, of which the following is a full, clear, and exact description, reference being had to the accompanying drawings, forming part of this specification.

My invention relates to that class of paper-rolls which are mounted on stands or within cabinets, and from which the paper is drawn and severed as required for use; and it has for its object the application to such rolls of novel printing devices whereby the store-keeper may print his card or other matter on the paper before severing it from the roll.

The novelty of my invention will be herein set forth, and specifically pointed out in the claims.

In the accompanying drawings, Figure 1 is a front elevation of a paper roll and holder embodying my invention. Fig. 2 is a sectional side elevation of the same within a case or cabinet. Fig. 3 is a plan view of the printing mechanism with a portion of the inking-ribbon broken away.

The same letters of reference are used to indicate identical parts in all the figures.

The usual paper-roll A is removably mounted in uprights B, secured to a bed-piece C, and covered or not, as desired, by a case or cabinet D. The paper is drawn from the roll under guide-rollers a and an intermediate rubber or other elastic cushion-plate E.

Supported in bearings F are two spools or rollers G H, around which is passed an endless inking-ribbon I, in line with and under the cushion-plate E, and over which ribbon the paper from the roll passes.

J is a type-plate carried by pivots, as at b, upon the ends of a forked lever K, pivoted as at f, and whose outer end projects through a vertical slot in the upright B, and a coincident slot in the case D, when the latter is used, and which outer end has a depressing button or knob c. To hold the type-plate in

a horizontal position suitable guides may be employed, for which purpose I have shown the four vertical guide-rods d, extending up through perforations in lugs e, projecting 55 from the type-plate at or near its corners.

It will be seen from this construction that the operator has only to depress the button c in order to lift the type-plate against the under side of the upper portion of the inking-ribbon, which is forced against the paper and the cushion-plate E, thereby printing the paper with the matter contained upon the type-plate, as will be readily understood. The paper is then drawn forward and severed 65 against the usual or other cutting-edge g.

To cause the traveling of the inking-ribbon after each depression of the button c to present a fresh inking-surface I provide a ratchet h upon the spool H, with which 70 ratchet a dog i upon the lever K engages, so that the re-setting of the type-plate and lever k by gravity will cause the dog to partially turn the ratchet and spool H and thereby shift the ribbon, as will be readily 75 understood.

Having thus fully described my invention, I claim—

1. The combination, with a suitable frame-work and a paper-roll journaled therein, of a 80 cushion-plate beneath which the paper from the roll passes, a vertically-reciprocating type-plate beneath the cushion-plate, a lever pivoted at one end to the type-plate and fulcrumed in the frame-work, the other end of 85 said lever extending outside the frame-work, in position to be operated by the hand of the operator, and an inking-ribbon passing over the type-plate, substantially as described.

2. The combination, with a suitable frame-work and a paper-roll journaled therein, of a cushion-plate beneath which the paper from the roll passes, guide-rods secured in the base of the frame-work, a vertically-reciprocating type-plate having perforated lugs through 95 which the said guide-rods pass, a lever pivoted at one end to the type-plate and fulcrumed in the frame-work, the other end of said lever extending outside the frame-work, in position to be operated by the hand of the 100 operator, a spool at each end of the type-plate, mechanism for turning the spools, and

an inking-ribbon carried by said spools passing over the type-plate, substantially as described.

3. The combination, with the paper-roll A,
5 of the cushion-plate E, inking-ribbon I, spools
G H, upon which said ribbon is carried, a type-
plate J, and a forked pivoted lever K, carry-
ing said type-plate and provided with a dog

i, engaging with a ratchet h upon the spool
H, substantially in the manner and for the
purpose specified.

EDWARD B. WESTON.
